UNITED STATES PATENT OFFICE.

WARREN H. HILL, OF PHILADELPHIA, PENNSYLVANIA, ASSIGNOR TO R. H. BEAUMONT CO., OF PHILADELPHIA, PENNSYLVANIA, A CORPORATION OF PENNSYLVANIA.

MATERIAL-HANDLING APPARATUS.

Application filed January 29, 1925. Serial No. 5,461.

My invention relates to material handling apparatus, and especially systems employing a loader for a hoisting bucket, such as skip-hoist systems now widely used for handling 5 coal, sand, gravel, etc., etc. In general, such a loader comprises a movable part or structure that delivers the material from a source of supply into the bucket when the latter is in position ready to receive it, and shuts off the 10 discharge at other times. I aim to improve the coaction between loader and bucket, so as to obviate spilling of material, and to minimize shocks in operation. How these and 15 other advantages can be realized through my invention will appear from the description hereinafter of a selected and preferred embodiment.

The drawing affords a fragmentary side view of a material-handling system of the 20 character described, certain parts being partly broken away and in section.

In the drawing, there is shown a bucket 10 and a discharge-controlling loader 11. The 25 source of supply of the material to be handled is represented by a hopper or bin 12 with an inclined outlet 13 at its bottom, on which the loader 11 is mounted. The loader 11 here shown has a substantially closed chute or 30 cowl portion 14, with an opening 15 for the passage of the material. The loader 11 and its chute 14 are swingable up and down across the path of the bucket 10 and about a horizontal axis 16, between a lower active position, shown in full lines, and an upper inactive position, indicated in dot-and-dash lines. 35 The loader 11 may be counterbalanced, as shown at 17, to facilitate this movement and to assist in keeping it in its upper inactive position except when the bucket 10 is in place ready to be filled.

As shown, the loader 11 may be swung down and up by the bucket 10 itself as it descends and rises. When the bucket 10 descends, its flanged lower corner 22 engages a hook device 23 pivoted to the loader 11 at 21, and thus pulls the loader down; when the bucket 10 rises, a part 24 at its upper edge engages the lower side of the chute 14, and thus causes the loader 11 to swing upward. The 45 hook device 23 may be equipped with cushion springs 25, to ease the shock when the descending bucket 10 catches the hook, as described in U. S. Patent No. 1,411,831 to Beaumont, granted April 4, 1922. In the present 50 instance, the path of movement of the bucket

10 adjacent the loader 11 is inclined. The bucket 10 may be raised and lowered by means of a cable 26 attached to the usual bail 27, and it may be guided by the usual wheels or rollers 28 and guide rails 29.

When the loader 11 is swung down into the active (full line) position by descent of the bucket 10, material from the chute 14 passes into said bucket by gravity until it extends up to the edges of the chute opening 15, when its flow is stopped by a sort of self-damming action, as set forth in U. S. Patent No. 1,359,212 to Webster, granted November 16, 1920. When the bucket 10 subsequently rises and the loader 11 swings upward, however, the chute mouth 15 lifts away from the material in the bucket, and additional material from the chute 14 runs out into the bucket 10. This supplemental delivery of material to the bucket 10 ceases, of course, when the rise of the chute 11 becomes sufficient to prevent flow from the outlet 13 into said chute and to cause the material in the latter to fall back thereinto.

Having thus explained the general operation of such a loader and bucket system, I will now proceed to describe and explain my invention as applied thereto.

Still referring to the drawing, it will be observed that when the loader 11 is in its active (full line) position, the cowl portion of the chute 14 extends over, substantially across, and into the mouth of the bucket 10,—which, as here shown, is cut down at its side toward said loader to permit this. In the present instance, the whole top of the bucket 10 is cut off sloping relative to its general length. Accordingly, the discharge opening 15, located (in the present instance) at the outer end of the cowl portion of the chute 14, is substantially at or adjacent the far side of the bucket 10. Instead, therefore, of delivering into the upper or "near" side of the bucket 10, the loader 11 delivers into its lower or "far" side, at a substantial interval beyond the near side or edge at 24. Hence the discharged material does not fill the upper side of the bucket 10, as would be the case if the chute 14 discharged into the near side of said bucket, adjacent its edge or corner at the part 24; on the contrary, there is a vacant space in the upper or near side of the bucket 10 corresponding to the natural slope or angle of repose of the material being loaded, as indicated by the line X.

When, therefore, the bucket 10 subsequently rises and the loader 11 swings upward, the vacant space X thus left in the upper portion of the bucket 10 accommodates 5 the supplemental flow or delivery of material from the chute portion 14 to the bucket 10 that then occurs, and thus prevents spilling or overflow of material from the top of said bucket. The considerable projection of the 10 bucket front beyond the far edge of the chute mouth 15 as shown serves as a hood to prevent spilling in that quarter.

In order to ease the engagement or impact 15 between the chute portion 14 and the bucket edge 24, I prefer to interpose a cushion means between them, such as a laterally flexible buffer spring 30. As shown, this buffer member 30 lies against the chute portion 14 at one end, but at the other end diverges outward there- 20 from, and laps over the angle bar 31 which forms the upper edge or corner of the chute

opening 15. When the bucket 10 rises, the rounded part 24 strikes against and rides along this member 30, whose resiliency cushions the shock; whereas, when the loader 11 swings downward, the buffer member 30 cushions its impact against the bucket edge 24 after the bucket 10 has been arrested by the buffer 25 32 at the bottom of its path of travel.

Having thus described my invention, I 30 claim:

In a system of the character described, the combination with a skip bucket of a loader therefor swingable across the path of movement of said bucket, with a laterally flexible 35 spring buffer along the lower side of said loader for engagement with the bucket.

In testimony whereof, I have hereunto signed my name at Philadelphia, Pennsylvania, this 22nd day of January, 1925.

WARREN H. HILL.
